UNITED STATES PATENT OFFICE

104,497

DESIGN FOR A PEDESTAL FOR MOTION PICTURE MACHINES

Albert Kindelmann, Floral Park, and Claude A. Soehl, Hensonville, N. Y., assignors to International Projector Corporation, New York, N. Y., a corporation of Delaware

Application February 25, 1937, Serial No. 67,862

Term of patent 14 years

To all whom it may concern:

Be it known that Albert Kindelmann, a citizen of the United States, residing in Floral Park, in the county of Queens and State of New York, and Claude A. Soehl, a citizen of the United States, residing in Hensonville, county of Greene, and State of New York, have invented a new, original, and ornamental Design for a Pedestal for Motion Picture Machines, of which the following is a specification, reference being had to

the accompanying drawing, forming part thereof.

Fig. 1 is a top plan view of a pedestal for motion picture machines, showing our new design.

Fig. 2 is a side elevational view thereof, and Fig. 3 is a front elevational view thereof.

We claim:

The ornamental design for a pedestal for motion picture machines as shown.

ALBERT KINDELmann.

CLAUDE A. SOEHL.
